Primary Examiner — Paula Greene(74) *Attorney, Agent, or Firm* — Burns & Levinson LLP;
Steven M. Mills(57) **CLAIM**

The ornamental design for an active headset, as shown and described.

DESCRIPTION

FIG. 1 is a front perspective view of the active headset, showing our new design, wherein the front face of the earphone ear pad adjacent the microphone is a mirror image of the front face of the opposite earphone ear pad illustrated in the figure, and the cord is drawn broken away to indicate indeterminate length;

FIG. 2 is right side view of the active headset, wherein the cord is drawn broken away to indicate indeterminate length; FIG. 3 is left side view of the active headset, wherein the cord is drawn broken away to indicate indeterminate length; FIG. 4 is a top view of the active headset; FIG. 5 is a bottom view of the active headset; and, FIG. 6 is a rear view of the active headset, wherein the cord is drawn broken away to indicate indeterminate length.
